UNITED STATES PATENT OFFICE.

CHARLES D. OESTERLEIN AND LOUIS H. BLOOD, OF CINCINNATI, OHIO, ASSIGNEES TO
THE OESTERLEIN MACHINE COMPANY, OF CINCINNATI, OHIO.

DESIGN FOR A MILLING-MACHINE FRAME.

53,687.

Specification for Design.

Patented Aug. 5, 1919.

Application filed April 17, 1919. Serial No. 290,871. Term of years 14 years.

To all whom it may concern:

Be it known that we, CHARLES D. OESTERLEIN and LOUIS H. BLOOD, citizens of the United States, residing at Cincinnati, Hamilton county, State of Ohio, (post-office address, 3301 Colerain avenue, Cincinnati, Ohio,) have invented a new, original, and ornamental Design for Milling-Machine Frames, of which the following is a specification, reference being had to the accompanying drawing, forming a part thereof.

The figure is a perspective view of a milling machine frame showing our new design.

We claim:—

The ornamental design for a milling machine frame, as shown.

CHARLES D. OESTERLEIN.
LOUIS H. BLOOD.
